LIFTING CONSTRUCTION FOR HELICOPTER
Pierre Yeo, 62 St. Jude, Fabreville, Quebec, Canada
Filed Apr. 17, 1964, Ser. No. 360,645
7 Claims. (Cl. 170—160.13)

The present invention relates to a helicopter and more particularly to a novel lifting construction therefor.

The device or construction of the invention is designed to improve the stability in helicopters by reducing the flapping effect of the wing blades. As is known, this flapping effect results from the difference in the lifting forces acting on a forward moving blade and a rearward moving blade disposed 180° from the former. This difference in lifting forces is of course due to the fact that with both blades given the same angle of incidence and with one blade travelling against the wind while the other travels with the wind, the general tendency is, therefore, to slant downwardly in the direction of the blade moving with the wind, the amount of slanting increasing from practically nothing when the blades are lengthwise in the wind to a maximum when they are crosswise in the wind; the net result being the effect known as "flapping" which insofar as stability of the helicopter is concerned, is the number one problem. No adequate solution has yet been proposed to overcome this difficulty.

It is, therefore, a main object of the invention to provide a lifting construction for helicopter wherein the flapping effect normally encountered in conventional helicopters is appreciably reduced.

Another object of the invention is to provide a construction of the above type which tends to equalize the total lifting forces acting on the blades whereby to avoid flapping normally existing where the lifting forces on the blades are unequal; the equalization being obtained by causing automatic adjustment of the angles of incidence of the blades as they rotate around the rotor mast.

The above objects may be obtained in a helicopter equipped with a lifting construction according to the invention which comprises: a central lifting rotor; a rotary member mounted on each side of the rotor; a blade mounted on each side of the rotor and having a leading edge and an axis of lift; a shaft secured on the inboard end of each blade and mounted on one of said members for rotation relative thereto about an axis parallel to and between the axis of lift and the leading edge; a compensating device operatively coupling said shaft and members and including an upper fluid pressure means adapted to cause rotation of the shaft in a direction opposite said one direction and a piping means joining the upper means together and, separately, joining the lower means together whereby to cause equalization of the lifting forces acting on the blades to thus avoid flapping.

In a preferred embodiment of the invention, the shaft axes are parallel to and offset from the axes of the members in opposite directions; the offset distance being such that the axes of said members are in line with the axes of lift of the blades.

A better understanding of the invention will be afforded by the description that follows of a preferred embodiment having reference to the appended drawing, wherein:

FIG. 1 is a perspective view of a helicopter, shown in dotted lines, with the lifting construction of the invention illustrated in full lines;

FIG. 2 is a perspective view, from below, showing on an enlarged scale, the lifting construction;

FIG. 3 is a top view, partly shown in cross-section, of the rotor construction;

FIG. 4 is a cross-sectional view through a vertical plane of the blade construction;

FIG. 5 is a cross-sectional view through one lever of the hydraulic compensating device;

FIGS. 6 and 7 are schematic views of a blade travelling against the wind and with the wind, respectively;

FIG. 8 is a schematic view of a set of helicopter blades intended to illustrate the flapping effect.

The construction which is intended to be applied to a helicopter 1 generally comprises a central lifting rotor 3 rotatable about a vertical axis and a pair of blades 5, 5' mounted on diametrically opposed sides of the lifting rotor 3 for rotation therewith; each blade having a leading edge 7 and an axis of lift 9 which is the locus of all centers of lift and extending parallel to the leading edge 7 of each blade. It will be noted that the said leading edges 7 of the blades 5, 5' face in opposite directions.

The incidence angle of the blades 5, 5' is obtained by means of a collective pitch mechanism comprising rotary members 11, 11' mounted for simultaneous limited rotation in reverse directions about an axis extending diametrically across the rotor 3; the said collective pitch mechanism being adapted, upon rotation of the rotary members 11, 11', to change the pitch of blades 5, 5'.

Shafts 13, 13' are secured on the inboard end of blades 5, 5' respectively and are mounted on the collective pitch mechanism for rotation about an axis extending parallel to and between the lift axes 9, 9' and the leading edges 7, 7.

In order to cause equalization of the lifting forces acting on blades 5, 5' to avoid flapping, a compensating device, preferably hydraulically operated, is provided for coupling shafts 13, 13' and rotary members 11, 11', respectively, the said compensating device including an upper fluid pressure means 15 and a lower fluid pressure means 17 (FIG. 5) for each blade, the said means being adapted to cause rotation of shafts 13, 13' in either of two directions.

The compensating device also includes piping means 19 (FIG. 4), joining the upper means 15 together and piping means 19' joining the lower means 17 together independently of piping means 19.

Preferably, shafts 13 and 13' are not mounted in alignment with the axes of their respective rotary members 11, 11' but offset therefrom as clearly shown in FIG. 2 and on a distance, in reverse directions, such that the axes of rotary members 11, 11' extend through the axes of lift 9, 9' of blades 5, 5', respectively.

The construction of the rotor of the invention will now be given in more details.

The central lifting rotor 3 is formed of a vertical mast 21 at the upper end of which is mounted the rotor hub 23, the latter being connected thereto by means of lateral axles 25, 25' which, as shown in FIGS. 2 and 3, allow hub 23 to pivot relative to mast 21 about the in-line transverse axes of axles 25, 25'.

As aforesaid, the collective pitch mechanism comprises the rotary members 11, 11' mounted for limited rotation or pivoting about a diametral axis of hub 23. Pivotal mounting of the rotary members 11, 11' may be through any conventional manner.

The collective pitch mechanism also includes a pair of radial arms 27, 27' fastened to rotary members 11, 11' to extend in opposite directions as clearly illustrated in FIG. 3. From arms 27, 27' depend vertical operating rods 29, 29' which are simultaneously operated by any suitable mechanism, not shown.

From the above description, it will be understood that the angle of incidence of blades 5, 5' may be changed by actuating the said operating rods 29, 29' thus causing blades 5, 5' both to move upward or downward from an upward position.

In the preferred case where shafts 13, 13' are mounted in offset relationship with respect to rotary members 11, 11' the collective pitch mechanism includes levers 31, 31' in the form of a heavy blade having one end secured to

one of the rotary members 11, 11' while shafts 13, 13' are rotatably mounted thereon in any conventional manner as that shown in FIG. 3 at 33.

As a part of the hydraulically operated compensating device above-mentioned, there is provided two L-shaped elements 35, 35' secured at one end to shafts 13, 13', respectively. The other end of the said L-shaped levers 35, 35' respectively extend into generally U-shaped notches 37, 37' formed at the forward end of levers 31, 31', respectively. It will be noted that the ends of levers 35, 35' entering into the said notches 37, 37' are formed with two flat surfaces.

As best illustrated in FIG. 5, the upper fluid pressure means of each lever 31 is a piston 39 displaceable in a cylinder 40 formed on the upper part of lever 31, the piston 39 having a piston rod 41 projecting out of cylinder 40 and having the outer end thereof applied on the top face of L-shaped element 35. Cylinder 40 communicates with a fluid conduit 43 which is part of the upper piping means 19', previously mentioned.

It will be understood from perusal of FIG. 5 that the lower fluid pressure means 17 is identical to the upper means 15 and, therefore, need not be described. It may only be added that its piston rod is applied on the lower flat surface at the end of L-shaped element 35.

It will also be understood that what has just been described in relation to the upper and lower fluid pressure means applies for both levers 31 and 31'.

The outlets 45' of the upper fluid pressure means 45 of both levers 31, 31' are interconnected by means of a flexible piping and, similarly, the outlets 45 of the lower fluid pressure means are also interconnected by a flexible conduit (referred to in FIG. 4 by numerals 19, 19').

It should however be noted that the said flexible conduits are independent of one another.

Finally, fluid pressure tubes 47, 47' are provided for supplying pressure fluid into the said flexible conduits respectively.

It should be pointed out at this time that the fluid 40 provided through tubes 47, 47' are always at the same pressure.

From the above description, the operation of the lifting construction of the invention can now be made.

Equal fluid pressure is applied against pistons 39 of the upper and lower fluid pressure means 15, 17 through tubes 47, 47'. Assuming that the angle of incidence of blades 5, 5' is changed by pulling simultaneously on rods 29, 29' and bringing them down an equal amount, the lifting force due to the wind action acting on blades 5, 5' will increase but, as will be understood, a greater amount for blade 5 moving against the wind than blade 5' moving with the wind. The action of the lifting force on blade 5 will cause an increase of pressure in the lower cylinder 40 of lever 31 and this increase pressure will in turn apply to the lower fluid pressure means 17 of blade 5' forcing the corresponding L-shaped element 35' to move upwardly and blade 5' to rotate counter-clockwise thus increasing the angle of incidence of the said blade 5' and amount corresponding to the increase in pressure brought about by blade 5. The net result will be a greater angle of incidence for blades 5' travelling with the wind than the corresponding angle of incidence of blade 5 travelling against the wind and equalization of the lifting forces acting on the two blades. This situation is illustrated in FIGS. 6 and 7 with the illustration of FIG. 6 being that of blade 5 and that of FIG. 7, blade 5'. The positions shown in dotted lines are those resulting from the above-described action.

As a result of the above action, blades 5 and 5' will tend to keep in a horizontal plane as shown in full lines in FIG. 8 rather than attempt to move slantwise as illustrated in dotted lines thus causing the flapping effect described previously.

Although a specific embodiment has just been described,

it will be understood that various modifications may be made without departing from the spirit of the invention, the scope of which is to be construed from the appended claims.

I claim:

1. In a helicopter, a lifting construction therefore, comprising:

(a) a central lifting rotor;
(b) a rotary member mounted on an axis each side of said rotor onto a hub solidly fixed to said rotor;
(c) a blade mounted on each side of said rotor and having a leading edge and an axis of lift;

(d) a shaft secured at one end on the inboard end of each blade and pivotally mounted at the other end on a lever, the said lever being solidly fixed to one of said members, said shaft rotating about an axis parallel to and between said axis of lift and said leading edge;

(e) a compensating device operatively coupling said shafts and members and including:

an upper fluid pressure means adapted to cause rotation of said shafts in one direction;

a lower fluid pressure means adapted to cause rotation of said shafts in a direction opposite said one direction; and

a piping means joining said upper means together and another piping means joining said lower means together independently of the first piping means whereby to cause equalization of the lifting forces acting on said blades to thus avoid flapping.

2. A lifting construction as claimed in claim 1, wherein said shaft axes are parallel to and offset from the axes of said members in opposite directions; the offset distance being such that the axes of said members are in line with the axes of lift of the blades.

3. In a helicopter, a lifting construction therefor, comprising:

(a) a central lifting rotor, rotatable about a vertical axis;

(b) a pair of blades mounted on diametrically opposed sides of said rotor for rotation therewith; each blade having a leading edge and an axis of lift; the leading edges of said blades facing in opposite directions;

(c) a collective pitch mechanism including members rotatably mounted on each side of a hub coaxially fixed to said rotor for simultaneous limited rotation in reverse directions; said mechanism adapted, upon rotation of said members, to change the pitch of said blades;

(d) a shaft secured at one end on the inboard end of each blade and pivotally mounted at the other end on a lever, the said lever being solidly fixed to one of the said members, said shaft rotating about an axis parallel to and between said axis of lift and said leading edge;

(e) a fluid pressure operated lift compensating device cooperatively coupling said shafts and mechanism and including:

upper pressure means for each shaft adapted to cause rotation of said shafts in one direction;
lower pressure means for each shaft adapted to cause rotation of said shafts in a direction opposite said one direction, and

piping means joining said upper pressure means together and further piping means joining said lower pressure means together independently of the other piping means, whereby to cause an equal fluid pressure to act on said upper and lower pressure means to thus equalize the lifting forces acting on said blade to avoid flapping.

4. A lifting construction as claimed in claim 3, wherein said shaft axes are parallel to and offset from the axes of said members in opposite directions; the offset distance

being such that the axes of said members are in line with the axes of lift of the blades.

5. In a helicopter, a lifting construction therefor, comprising:

- (a) a central lifting rotor, rotatable about a vertical axis;
- (b) a pair of blades mounted on diametrically opposed sides of said rotor for rotation therewith; each blade having a leading edge and an axis of lift; the leading edges of said blades facing in opposite directions;
- (c) a collective pitch mechanism including axle members mounted on opposite sides of said rotor for rotation therewith about said vertical axis; said axle members being also mounted for simultaneous limited rotation in reverse directions about an axis extending diametrically across said rotor; said mechanism adapted upon rotation of said axle members to change the pitch of said blades;
- (d) said mechanism further including a lever secured on each axle member for limited rotation therewith in a plane normal to the diametral axis of said axle members;
- (e) a shaft secured on the inboard end of each blade and mounted on the corresponding lever for rotation relative thereto about an axis extending parallel to, between said lift axis and said leading edge and offset from the axis of said axle members;
- (f) an L-shaped element fastened to each shaft and having a portion thereof projecting in a notch cut out of the corresponding lever;

10

15

20

25

(g) an upper and a lower hydraulic piston in each lever having piston rods connected to two opposite sides of the portion of the corresponding element adapted, upon rotation of the lever, to cause rotation of the corresponding shaft, and

(h) piping means joining said upper pistons together and said lower pistons together, whereby to cause an equal fluid pressure to act on said upper pistons and said lower pistons to thus equalize the lifting forces acting on said blades to avoid flapping.

6. A lifting construction as claimed in claim 5, wherein the piping means joining the upper pistons is under the same hydraulic pressure as the piping means joining said lower pistons.

7. A lifting construction as claimed in claim 5, wherein said levers are mounted on said axle members to extend in opposite directions and a vertically operated leverage mechanism is provided to cause simultaneous rotation of said axle members in opposite directions of rotation.
